US00D618085S

(12) **United States Design Patent**
Lin et al.

(10) **Patent No.:** US D618,085 S
(45) **Date of Patent:** ** *Jun. 22, 2010

(54) **TWISTED STUD TO PLATE TIE**

(76) Inventors: **Jin-Jie Lin**, 5956 W. Las Positas Blvd., Pleasanton, CA (US) 94588; **Prentiss Porter Douglass**, 5956 W. Las Positas Blvd., Pleasanton, CA (US) 94588; **Bryan Morgan Ables**, 5956 W. Las Positas Blvd., Pleasanton, TX (US) 94588; **Sam Thomas Hensen**, 5956 W. Las Positas Blvd., Pleasanton, CA (US) 94588

(*) Notice: This patent is subject to a terminal disclaimer.

(**) Term: **14 Years**

(21) Appl. No.: **29/296,983**

(22) Filed: **Oct. 31, 2007**

(51) LOC (9) Cl. **08-05**

(57) **CLAIM**

The ornamental design for a twisted stud to plate tie, as shown and described.

DESCRIPTION

FIG. 1 is a perspective view of the twisted stud to plate tie showing our design.

FIG. 2 is a top plan view of the twisted stud to plate tie showing our design.

FIG. 3 is a bottom plan view of the twisted stud to plate tie showing our design.

FIG. 4 is a left side elevation view of the twisted stud plate to tie showing our design.

FIG. 5 is a right side elevation view of the twisted stud plate to tie showing our design.

FIG. 6 is a front elevation view of the twisted stud plate to tie showing our design; and,

FIG. 7 is a back elevation view of the twisted stud plate to tie showing our design.

1 Claim, 4 Drawing Sheets
